Eugene C. Brown
ATTORNEY.

UNITED STATES PATENT OFFICE

SAMUEL B. NEIKIRK, OF TROY, MISSOURI

SAND-BLAST NOZZLE

Application filed November 18, 1927. Serial No. 234,132.

This invention relates to apparatus for sand blasting and particularly to the construction of a nozzle which will concentrate the stream or jet of sand issuing from the nozzle and project it with greater force than those heretofore employed.

One of the objects of my invention is to provide a nozzle which will not be rapidly worn away by the sand as it issues from the mouth of the nozzle. Another object is to provide a nozzle which will produce a stronger blast than those now in use with the same air pressure.

In the following description I shall refer to the accompanying drawings in which—Figure 1 is a diagrammatic illustration of an apparatus employed in sand blasting; Figure 2 is a longitudinal sectional view of a sand blast nozzle embodying my invention; and Figure 3 is a longitudinal section of my nozzle illustrating the action of the sand in its passage therethrough.

As is well understood by those familiar with sand blasting, the sand is fed from a receptacle such as shown at 10 in Fig. 1, which is usually maintained under an air pressure of about 75 pounds. The nozzle 12 is secured by a coupling 14 to a hose 15 connected to the outlet of the sand receptacle.

I have discovered that the defects above mentioned may be overcome by providing the inner end of the nozzle with an inlet chamber 17 having an elongated conical wall extending to the line 18^a in Figs. 2 and 3, which gradually concentrates the homogeneous mixture of air and sand without causing any separation as it enters the tapering bore 18 of the nozzle. By comparing the elongated conical inlet chamber of my nozzle with the short outward flare of prior nozzles, such as shown in the patents below mentioned, it will be observed that the inclined walls of the elongated chamber serve to guide the mixture toward the axis of the nozzle without the sudden or abrupt change which necessarily takes place when the blast strikes the short abrupt flare of said prior devices.

In all prior sand blast nozzles with which I am familiar of the type employed with apparatus in which a homogeneous mixture of

air and sand forming the blast is conveyed through a hose direct to the nozzle, the inner end of the nozzle is merely flared or provided with a short outward taper to meet the inner walls of the hose in order to avoid any ledge or corner which would catch the sand. Such prior constructions are shown for instance in U. S. Patents Nos. 561,483 and 979,897 or in French patent to Sloan No. 513,375 February 14, 1921. In these prior devices the sand will clog just at the inner end of the flaring opening. When this occurs the separated sand seems to hug the inner walls of the bore of the nozzle and at the outlet end produces a cutting action which very rapidly cuts away the metal and produces an irregular enlarged discharge opening which greatly reduces the efficiency and shortens the operative life of the nozzle.

The blast in my nozzle remains substantially homogeneous throughout and is gradually converged in its passage through the bore of the nozzle. I have found by actual use of these nozzles that there is no tendency to cut the metal at the outlet or discharge end of the nozzle and hence that I have overcome the very radical defect in the nozzles of said prior construction. In addition to this, however, I have greatly increased the efficiency of the blast. The velocity of the blast is increased in its passage through the tapering bore so that the cutting action of the blast upon the work is increased several fold. The force of the concentrated blast issuing from the nozzle permits the workman to hold the nozzle a greater distance from the work and this permits the sand particles, which are very hot as they issue from the nozzle, to be cooled before they strike the work so that they will not injure the same. This latter feature is also important in the operation of sand blasting marble and other surfaces.

I claim:—

A nozzle for sand blast apparatus having an unobstructed elongated inlet chamber having a length greater than the diameter at its mouth and provided with a conical wall gradually inclined to the axis of the nozzle and a bore extending therefrom and having a slight taper from the inner end to the discharge

opening of the nozzle, the converging walls of the conical inlet chamber causing the gradual convergence of the mixture of sand and air entering at the mouth of the nozzle, thereby preventing any separation of the sand particles or accumulation of sand at the junction of the inlet chamber and bore of the nozzle.

In testimony whereof I affix my signature.
